Assistant Examiner—R. Johnson

(74) *Attorney, Agent, or Firm*—Arent Fox LLP

CLAIM

The ornamental design for a surgical scrub pants with mesh, as shown and described.

DESCRIPTION

FIG. 1 is a front view of surgical scrub pants with mesh showing our new design;

FIG. 2 is a rear view of the design shown in FIG. 1; and,

FIG. 3 is a side view of the design shown in FIG. 1, the opposite side view being a mirror image thereof.

The elements shown in broken lines are for illustrative purposes only and form no part of the claimed design.
